(57) **CLAIM**

We claim the ornamental design for a tool handle, as shown and described.

DESCRIPTION

FIG. 1 is a top, rear perspective view of a tool handle showing the claimed design in an open position of use;

FIG. 2 is a right side view thereof;

FIG. 3 is a left side view thereof;

FIG. 4 is a top view thereof;

FIG. 5 is a bottom view thereof;

FIG. 6 is a rear view thereof;

FIG. 7 is a front view thereof; and,

FIG. 8 is a right side view of the claimed design in a closed position of use.

The broken lines shown in the drawings represent environmental structure and form no part of the claimed design.
